Frank M. Ashley

HIS ATTORNEY

UNITED STATES PATENT OFFICE

PETER A. FARRELL, OF BROOKLYN, NEW YORK

SIGN

Application filed May 6, 1929. Serial No. 360,623.

My invention relates to signs.

The object of my invention is to provide a sign which is practically fire-proof, moisture proof, and non fading, and which may be illuminated at night.

A further object is to provide a sign in which both the entire face of the sign as well as the letters may be simultaneously illuminated and may be colored as desired to provide an ornamental effect or appearance.

A further object is to provide a sign which may be made at a low cost.

In describing my improved sign I will refer to drawings which illustrate my invention as used for indication the number of a dwelling or business address, or for use on an automobile, etc. and in this form my device is constructed as a small portable device, but it may be also constructed for use as a large fixed sign for use above a store or for any other use for which it may be adapted.

One of the principal objects of my invention is to provide an illuminated sign which may be brilliantly illuminated by one or more small lamps of low candle power, to provide a sign that may be economically illuminated.

Referring to the drawings which illustrate my invention,

Fig. 1 is an elevational front view of a sign embodying my invention, and shown in its position in a frame supported in a casing.

Fig. 2 is a cross sectional view of the device taken on line 2—2 of Figure 1.

Fig. 3 is an illustrational view indicating the four layers of material, which when held together firmly, may be made and sold independent of the casing and illuminating means.

Fig. 4 is an end view showing a frame construction for holding the four layers of material shown in Figure 3, together, the frame being shown partly in cross section.

I may also provide a sign embodying my invention having but three sheets or layers of material.

A—indicates a thin sheet iron casing which is plated with tin or chromium, and formed with a rectangular shaped opening A'—in its front side, and a similar shaped opening

A²—in its opposite side which is closed by a removable metal sheet A³—which is plated on its inner side A⁴ with chromium to serve as a reflecting surface for reflecting light thru a translucent sign located in the opening A'. The ends of the casing are closed by walls formed integral with the bottom A⁵—of the casing, and bent upwardly and soldered to the end walls of the casing to provide a water tight chamber A⁶—when the sign frame B— and sign elements held thereby, are in position in the front opening A'. One or more electric lamps C— are supported on the end walls A⁷— and electric conductors C'— lead therefrom to a source of electric supply, such as a house circuit or storage battery having a voltage suitable for use with the lamps used in the casing. If desired, the reflecting sheet A³— may be soldered in permanent relation to the casing and the frame B— removed to afford access to the chamber A⁶—in renewing the lamps from time to time.

The frame B— is formed as illustrated in cross section in Figure 2—to provide a flange portion B'— which rests against the face portions A⁸— of the casing, and an inwardly extending portion B²— which extends entirely around the frame, and having its edge portion bent inwardly as shown to provide an annular groove D— which also extends entirely around the frame.

The frame also embodies a front flange portion B³— having its inner edge portions B⁴— bent inwardly, the inner side of which serves as an abutment for the front plate E— of the sign to rest against and form a tight joint between the casing and said plate. The frame B— fits in the opening A'— in substantially water tight relation, and is held by the edge portions of the casing firmly therein with the flange faces B' in close contact with the face portion A⁸— of the casing, and in removable relation thereto.

The sign proper comprises the elements to be illuminated, and consists of four layers of material held firmly together, either by transparent cement located between the abutting surfaces of the layers, such as silicate of soda, or by being held in a frame of metal or other suitable material which will prevent

moisture from entering between the layers, and to permit the elements thus assembled to be sold as a separate article of manufacture.

The layers comprise a front plate E— of transparent material such as glass; a sheet F— of thin translucent material or material having small interstices thru which light may pass, and which may be colored so that light will show its color, and which may be cut to provide letters and figures or other signs, and cut portions being made like a stencil is made; G— indicates a thin sheet of material such as gelatin, which may be transparent or colored, depending upon the color of the sheet F—, and when used in the casing, upon the color of the lamp bulb C. H— indicates a plate of translucent material such as glass, and usually white or cream colored, but it may be of any desired color required to make a sign embodying the invention herein disclosed.

I have discovered that gelatin in a thin sheet may be illuminated brilliantly with a relatively small amount of light when colored red or blue, and I therefore prefer to make the sheet G— of this material. The sheet F— I prefer to make of thin paper such as tissue paper, and of a color which contrasts with the color of the gelatin sheet G. The sheet H— is generally made of cream color or white glass, but may be made of the same color as that of the sheet G— to reinforce the color brilliancy of said sheet. The sheet G— has the figures or signs formed therein, as illustrated in Figure 1, by cutting out the portions corresponding to the longitudinally extending lines G'— as will be readily understood.

When used with the lamp C— the bulb may be colored to correspond with the color of the gelatin sheet to further add to the color effect.

When used in the casing A, the gelatin may be transparent and the sheet F— colored blue, and the lamp bulb colored red, and the lettering will then show red with the face of the sign showing blue and red, if the plate H— is also colored red.

I may make the sheet F— of blue gelatin and the sheet G— of red gelatin, and the sheet H— of cream color, and the face of the sign will then appear as blue with a red letter or number, or vice versa, the sheet G of blue and the sheet F— of red.

By this combination of sheets and colors which contrast, I may provide signs which are attractive in appearance at a low cost.

When the sheets are assembled as illustrated in Figure 1, they may be held in the frame B— by hooks I—I— etc., one end of which is hooked to the frame and rests in the channel or groove D— and the other end of which is bent over the edge portion of the rear plate H— as shown in Figure 2, and presses the front plate firmly against the in-

ner face of the edge portions B— of the frame.

The principal reason for using a translucent back plate, as H— is to provide a more even illumination of the entire display surface of the sign. I may use a sign having but three sheets by using a translucent back plate, a colored film such as red gelatin with the numbers formed therein, and a transparent front plate. Assuming the back plate to be red, the gelatin sheet blue, and the back plate white, the sign would present a white number on a blue field.

My invention therefore comprises broadly the use of a translucent back plate, a film or sheet of colored material either translucent or fabricated to pass light and illuminate the face of the sign to correspond with the color of the film, and a front sheet of transparent material such as glass, to provide a moisture proof sign when held together as above set forth.

Having thus described my invention I claim as new:

1. A sign comprising a translucent opalescent back plate, a sheet of thin colored gelatin, a translucent sheet of different color from that of said sheet of gelatin, and a front plate of transparent material, said translucent sheet having characters formed therein by removing portions thereof, and means for holding said sheets firmly between said plates.

2. A sign comprising a translucent back plate, a sheet of thin colored gelatin located adjacent thereto, a sheet of translucent material having a different color from that of said sheet of gelatin with characters formed therein by removing portions thereof, and a front plate of transparent material, all held firmly together in contact to prevent moisture from entering between said plates.

3. A sign of the character described, comprising a casing having a front opening and adapted for interior illumination, a series of parallel sign plates located in said opening and including in series from front to back, a transparent front plate of glass, a translucent plate having characters stenciled therein, a third plate of colored gelatin and a plate of translucent glass, the said plates being enclosed in a frame and held in close contact.

In testimony whereof I have affixed my signature.

PETER A. FARRELL.
